(57) **CLAIM**

The ornamental design for an expansion valve, as shown and described.

DESCRIPTION

FIG. 1 is a front perspective view of an expansion valve showing our new design;

FIG. 2 is a rear perspective view thereof;

FIG. 3 is a front view thereof;

FIG. 4 is a rear view thereof;

FIG. 5 is a top view thereof;

FIG. 6 is a bottom view thereof; and,

FIG. 7 is a left side view thereof, the right side view being a mirror image thereof.

The broken lines are for the purpose of illustrating portions of the expansion valve and form no part of the claimed design.

1 Claim, 7 Drawing Sheets
